UNITED STATES PATENT OFFICE.

CHARLES J. DIEGES, OF NEW YORK, N. Y.

DESIGN FOR A PLAQUE.

43,034.

Specification for Design.

Patented Sept. 24, 1912.

Application filed July 22, 1912. Serial No. 710,994. Term of patent 7 years.

To all whom it may concern:

Be it known that I, CHARLES J. DIEGES, a citizen of the United States, residing in the borough of Manhattan, city, county, and State of New York, have invented a new, original, and ornamental Design for a Plaque, of which the following is a specification, reference being had to the accompanying drawing, forming part thereof.

The figure is a front elevation of the plaque, showing my new design.

I claim,

The ornamental design for a plaque, as shown.

CHARLES J. DIEGES.
